STAND FOR PENS

Jacob Feinberg, Brooklyn, N. Y.

Application October 5, 1933, Serial No. 692,270

3 Claims. (Cl. 120—108)

This invention relates to new and useful improvements in a stand for pens.

The invention has for an object the construction of an article as mentioned which is characterized by sheet material having its edges turned into conical shaped pen supports having bottom apexes substantially adjacent each other and inclined away from each other towards the top.

Still further the invention proposes particularly the provision of a web portion between the conical shaped pen supports.

Still further the invention proposes in an article as mentioned the provision of a pair of conical shaped pen supports connected with webs adjustably connected with each other so that the angular relation of these pen supports may be controlled.

Furthermore as another object of this invention, it is proposed to construct an article as mentioned which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure.

Fig. 1 is a perspective view of an article constructed according to this invention.

Fig. 2 is a front elevational view of Fig. 1.

Fig. 3 is a plan view of Fig. 1.

Fig. 4 is a view similar to Fig. 3 but illustrating another embodiment of the invention.

Fig. 5 is another view similar to Fig. 3 but illustrating a still further embodiment.

Fig. 6 is a side elevational view of the form illustrated in Fig. 5 but seen as though looking in the direction of the line 6—6 of Fig. 5.

Fig. 7 is another view similar to Fig. 2 illustrating a still further embodiment of the invention.

Fig. 8 is a side elevational view looking in the direction of the line 8—8 of Fig. 7.

Fig. 9 is another plan view similar to Fig. 3 but illustrating another embodiment of the invention.

Fig. 10 is a front elevational view of Fig. 9.

Fig. 11 is a side elevational view of another embodiment of the invention.

Fig. 12 is a perspective view of conical shaped pen supports constructed according to a modification of the invention, to be used in a combi-

nation stand for ink bottles, corks and pens as previously described.

Fig. 13 is a similar view to Fig. 6, but showing another embodiment of the invention.

The combination stand for an ink bottle, cork and pens, includes a sheet of material having its edges turned into conical shaped pen supports 10 and 11 having the bottom apexes 12 substantially adjacent each other but slightly spaced and inclined away from these apexes towards the top. 10 These conical shaped pen supports are separated by a web portion 13. Examining Fig. 3 it will be readily understood the manner in which the sheet is bent so as to form the conical shaped pen supports. The dot and dash lines 14 in Fig. 2 schematically illustrate pens engaging within the pen supports. 15

An ink bottle support is attached to the lower area of the web 13 and comprises a base disc 15 upon which an ink bottle may rest and is formed 20 at the periphery with several clips 16 adapted to engage frictionally against the sides of the bottle. One of these clips engages against the lower portion of the web portion 13 and is of a width so as to engage in between the space between the 25 apexes 12 of the conical shaped pen supports. A bolt 17 serves to secure this clip to the web portion and so connect the ink bottle support with the pen supports. A feature lies in the fact that just one bolt 17 is used to connect the clip with 30 the web portion in that the sides of the clip engage against the sides of the conical shaped pen support portions 10 and 11 and so prevent turning one of these parts.

The dot and dash lines 18 schematically indicate an ink bottle resting upon the members 15. A cork support is attached upon the upper area of the web and comprises a ring 19 into which a cork may be placed and formed with a side finger 20 engaging against the rear side of the 40 web 13 and secured in place by a rivet 21, eyelet bolt and nut, etc. The cork support 19 is arranged so as to be disposed upon the horizontal and slightly below the top edge of the web portion 13 as may be recognized by inspecting Fig. 2. This arrangement is desirable in that then the cork is not readily viewable from the front. 45

In Fig. 4 a modification of the invention has been disclosed in which it is provided with a cork support 22 comprising a piece of wire bent into 50 a substantially annular portion but having separated ends so as to form a spring clip to engage the cork. This wire is secured by a bolt 21 upon the web portion as previously described. This form of the invention also distinguishes in that 55

the conical shaped pen supports 10 and 11 are formed with top flanges 23 having a plurality of spaced cuts 24 completely about the peripheries and extending slight distances down into the body 5 of the conical shaped pen supports as clearly illustrated in Fig. 4. This arrangement gives the pen supports a certain degree of resiliency so that pens may be forced therein and maintain their position under resilient stress. In other respects 10 this form of the invention is similar to the previous form and similar parts may be recognized by corresponding reference numerals.

In Figs. 5 and 6 another modified form of the invention has been disclosed which is substantially 15 identical to the form illustrated in Figs. 1-3 except for the construction of the ink bottle support. According to this form of the invention the ink bottle support comprises a strip of material which has a central portion 25 engaged intimately against the front side of the web 13. It has continuations from the portions 25 continued into annular portions 27 adapted to partially encircle the ink bottle. These continuations 27 terminate in outturned ends 28 which 20 serve the double function of finishing the ends of the continuations 27 and constituting hooks for receiving an elastic band or other resilient element to draw the continuation 27 tightly against the sides of the ink bottle. The strip 27 is also formed with several feet 29 extending from the bottom edge so that the device may rest upon a table or other flat surfaces. The strip 27 may 25 also be formed without feet 29.

In Figs. 7 and 8 another modified form of the 30 invention has been disclosed which is very similar to the form illustrated in Figs. 1 and 2 inclusive except for the construction of the ink bottle support. According to this form the ink bottle support comprises a band 30 of circular shape attached by a bolt 31 upon the lower portion of the web portion 13 of the pen supports. This band is of annular shape and has its ends adjacent each other and engaged by a clamping screw 33 so that the band may be clamped upon an ink 35 bottle. The dot and dash lines 34 illustrate a square ink bottle with the clamp attached in place.

In Figs. 9 and 10 another modified form of the 40 invention is disclosed which also distinguishes merely in the construction of the ink bottle support. According to this form the ink bottle support comprises a band of material 35 which is secured at the center by a bolt 36 upon the web portion 13 of the bottle support. This band 35 is of semicircular shape and at the ends has pins 37 to which a spring 38 or other resilient element is attached. This spring 38 is so constructed that it tends to assume a semicircular shape and in conjunction with the band 35 is capable of 45 clamping against the bottle.

In Fig. 11 a modified form of the invention has 50 been disclosed in which the device comprises merely an ink bottle support with a cork holder. More particularly the device comprises a plate 40 having several projecting clips 41 for engaging and clamping against the sides of the bottle. A

finger 42 also projects from the member 40 and has a horizontal portion formed with an aperture so as to be able to hold the cork of a bottle indicated by the dot and dash lines 43.

In Fig. 12 another variation of the invention has 5 been disclosed which shows an arrangement whereby the angular relation of the pen supports may be varied. According to this form each of the pen supports comprises a sheet of material having a web portion 45 and turned at one end 10 producing a conical shaped pen support portion 46. Two of these units are arranged so that the web portions are directly over each other. These web portions are formed with substantially horizontal arcuate slots 47 engaged by bolts and nuts 15 48 so that they may be clamped in various positions. The advantages of this adjustable arrangement is of a double nature, first of all it allows for changing the angular position of the pen supports which is desirable from an esthetic 20 point of view and it also allows variation of the distance between the conical shaped portions 46 so as to better engage the edges of a clip engaged between the lower ends or apexes of the conical shaped pen supports and against the web, this 25 clip being for the purpose of attaching an ink support element upon the pen supports.

In Fig. 13 the clamp is attached to the neck of the bottle, and the bottom of the pen holder is provided with spherical legs 48.

It is to be understood that my device may be 30 made of any metal, composition or any other suitable substance.

While I have shown and described the preferred 35 embodiment of my invention, it is to be understood that I do not limit myself to the precise construction herein disclosed and the right is reserved to all changes and modifications coming within the scope of the invention as defined in the appended claims.

Having thus described my invention, what I 40 claim as new, and desire to secure by United States Letters Patent is:—

1. A support, comprising means including a portion adapted to support sheet material, and a 45 sheet of material comprising a web portion having its ends turned into conical shapes with their apexes close together and diverging towards their bases for pen supports and attached upon said portion.

2. A support, comprising means including a portion adapted to support sheets of material, and sheets of material having one of their ends turned into conical shaped pen supports and attached on said portion, said sheets having overlapping 55 webs adjustably connected.

3. A support, comprising means including a portion adapted to support sheets of material, and sheets of material having one of their ends turned into conical shaped pen supports and attached on said portion, said sheets having overlapping webs adjustably connected, and bolts engaged through openings in one of said webs and through slots in the other of said webs for holding said webs in relatively adjusted positions.

JACOB FEINBERG.
